PROPELLER

Walter W. Everts, Baltimore, Md., assignor to
 Everel Products Corporation, Baltimore, Md.,
 a corporation of Maryland

Application February 4, 1937, Serial No. 124,120

7 Claims. (Cl. 170—162)

My invention relates to propellers.

An important object of the invention is to provide a propeller for operation within a fluid, such as a gas or liquid, whereby the propeller may be advantageously used in connection with aircrafts, boats including surface ships or submarines, and fans used for ventilating purposes or the like.

5 A further object of the invention is to provide a propeller of the above mentioned character, which is automatically actuated by centrifugal force, to vary its pitch, as the pressure of the fluid medium within which its operating varies at any given speed of rotation.

10 A further object of the invention is to provide a propeller of the above mentioned character, having opposed centrifugally balanced portions, for reducing friction and permitting of the free turning movement of the propeller blade upon its axis for varying its pitch.

15 A further object of the invention is to provide a propeller of the above mentioned character so constructed that the fluid or air load acting upon the same is opposed by the action of centrifugal force, these two forces balancing each other to 20 find the correct angle of the propeller, to eliminate vibration and bending moments and gyroscopic forces.

25 A further object of the invention is to provide a propeller of the above mentioned character embodying a single blade, whereby the propeller may be driven at an increased maximum speed with efficiency.

30 A further object of the invention is to provide strong and simple means for assembling the various parts of the device, for effecting a strong union, and permitting of the proper access of parts when desired.

35 In the accompanying drawings forming a part of this application and in which like numerals are employed to designate like parts throughout the same,

Figure 1 is a perspective view of a propeller embodying my invention,

40 Figure 2 is a front elevation of the propeller, upon an enlarged scale, parts being broken away,

Figure 3 is a longitudinal section taken on line 45 3—3 of Figure 2,

Figure 4 is a transverse section taken on line 4—4 of Figure 2,

50 Figure 5 is a similar view taken on line 5—5 of Figure 3,

Figure 6 is a side elevation of the propeller with the bearing device removed,

55 Figure 7 is an exploded perspective view of the bearing device,

Figure 8 is an assembled perspective view of the inner bearing unit of the bearing device,

Figure 9 is an end elevation of the propeller showing the blade at the minimum pitch,

Figure 10 is a similar view showing the blade 5 at the maximum pitch, and,

Figure 11 is a similar view showing the blade swung past the maximum driving pitch position.

In the drawings, wherein for the purpose of illustration is shown a preferred embodiment of 10 my invention, the numeral 10 designates the blade of the propeller, which propeller may be formed of suitable material, such as aluminum, an aluminum alloy, bakelite, wood or the like. The propeller is preferably formed integral and 15 comprises a hub portion 11, carrying a shank 12 upon one side which is integral with the hub and blade 10. The hub also has a counterweight shank or member 13 integral therewith, arranged 20 opposite the shank 12. The hub 11 projects upon opposite sides radially beyond the shanks 12 and 13, in the direction of the plane of rotation of the propeller. It might be stated at this point that the action of centrifugal force upon the 25 blade 10 and shank 12 is balanced by the action of centrifugal force upon the counterweight shank or member 13, these forces of course operating in opposite directions. This reduces friction upon the engaging parts and permits of the proper movements of the propeller, to be described.

30 As more clearly shown in Figure 6, the hub 11 is provided with an opening 14, having opposed cylindrically curved walls 15, oppositely arranged, and opposed radial extensions 16, having side 35 walls 16' and end walls 17.

The numeral 18 designates a propeller or driving shaft, upon which is rigidly mounted a sleeve 19, for rotation therewith. This sleeve carries opposed pivot elements 20, preferably in the form 40 of tubular stub-shafts. These stub-shafts are radial with respect to the driving shaft 18. The numeral 21 designates an inner bearing unit as a whole, comprising semi-cylindrical bearing elements 22, having reduced innerfitting edges 23, 45 as shown. These inner bearing elements 22, when assembled, produce a tubular structure, having segmented flanges 24, slidably receiving the sleeve 19 and positioned upon opposite sides of the stub-shafts 20, as shown. Formed integral 50 with the bearing elements 22 are enlargements, webs, or lugs 25, having straight parallel side faces 26, and cylindrically curved oppositely arranged faces 27. The webs 25 are provided with oppositely arranged cylindrical radial openings 55

28, pivotally receiving the radial stub-shafts 20, as shown. It is obvious that the inner bearing elements 22 are placed upon the sleeve 19, after the sleeve is applied to the drive shaft 18. The 5 numeral 29 designates outer bearing elements or blocks, which are elongated and rectangular in longitudinal and transverse section. These outer bearing elements or blocks are oppositely arranged and have longitudinally extending recesses 30, pivotally receiving the webs 25. These recesses include curved tops 31 and straight side walls 32, as shown. The outer bearing elements or blocks 29 have grooves or notches 33 at their radially outer sides. The outer blocks or bearings are longer than the width of the hub 11, and 10 are adapted to project beyond same, as shown. The outer bearings or blocks 29 are placed upon the webs 26, and the entire assembled bearing unit is then inserted into the opening 14 of the 15 hub 11 of the propeller.

Adapted to be arranged upon the opposite face of the enlarged hub 11 are discs 34, which are circular, and are clamped to the hub 11 by bolts 35 or the like. These discs have openings 36 formed 20 therein, corresponding to the shape of the openings 14. The openings 36 have oppositely arranged curved walls 37, adapted to coincide with the curved walls 15 of the opening 14 and sides 38 to coincide with the sides 16, and end walls 39 which are arranged slightly inwardly of the 25 end walls 17. The end walls 39 engage within the notches or grooves 33, while the side walls 32 of the outer bearing elements or blocks 29 snugly engage the side walls 38 and also the side walls 35 39. The sleeve 19 is spaced from the inner wall 40 of the inner tubular bearing unit 21, and this permits of the turning of the propeller upon its axis 10', to vary its pitch. The centers of the pivots or stub-shafts 20 are in alignment with the 45 line 10' of the propeller blade when the propeller blade is in the true radial position. In addition to the turning movement of the propeller upon its longitudinal axis about the longitudinal line 10', the propeller blade is adapted to be turned upon 50 its transverse axis, about the center of the cylindrically curved face 27 of the inner bearing unit. The propeller is therefore adapted to be turned upon its transverse axis in a direction longitudinally of the drive shaft 18. By virtue of 55 this turning movement, the air load which is opposed by the action of centrifugal force, tends to swing the propeller forwardly in a direction longitudinally of the drive shaft, which action is balanced by the action of centrifugal force tending to return the propeller to the true radial position with respect to the drive shaft. These two forces will therefore automatically find the correct angle of the propeller, with respect to the longitudinal axis of the drive shaft, to thereby 60 eliminate vibration of the propeller, bending moment and gyroscopic forces.

When the propeller is rotating at sea level, as applied to an aeroplane or the like, and in the direction of the arrow, where the pressure of the 65 atmosphere is at the maximum, the propeller has the minimum pitch, regardless of variations of speed. The radial axis of the centrifugally operated portion or hub 13 is inclined or disposed at an acute angle with respect to the working face 70 of the propeller blade. The position of the blade 10 at this minimum pitch is shown in Figure 9 and also the position of the enlarged hub portion 11, the walls of the sleeve 19 now engaging the curved side walls of the inner bearing unit 21, thus limiting the minimum pitch of the pro- 75

peller blade. If the rotating propeller rises to a higher altitude, the resistance of the air upon the unbalanced areas of the blade decreases. The trailing area 16a of the blade is greater than the leading area 15a and these surfaces are unbalanced so that the action of the air pressure thereon tends to turn the propeller upon its axis 10' to reduce its pitch. The action of centrifugal force upon the radially enlarged portion or hub 11 is now sufficient to cause this enlarged portion 10 to overcome this air pressure action and to turn the propeller upon the pivots or stub-shafts 20 in a direction to increase the pitch of the propeller. Figure 10 shows the centrifugally operated hub portion 11 at the true radial position at 15 which time the blade 10 will have the maximum propelling pitch. When the resistance of the air exceeds the driving action of the propeller, as when making a power drive, the pressure upon the trailing area 16a, which is greater than the 20 leading area 15a, will serve to overcome the action of centrifugal force upon the radially enlarged centrifugally operated portion of hub 11 and will turn this radially enlarged portion to the extreme position, as shown in Figure 11, which 25 is limited by the contact of the walls of the sleeve 19 with the ends of the inner bearing unit 21, thereby further increasing the pitch of the propeller blade beyond the maximum propelling pitch. 30

When the aeroplane is in a nose dive, with the engine idling, or dead, the air pressure acting upon the propeller will tend to swing the same upon its transverse axis about the cylindrical surface 21, which action is opposed by that of 35 centrifugal force, but this rearward swinging movement will relieve the propeller of strains, to a considerable extent, and will prevent rattling.

A further advantage of my propeller is that it has only a single blade and may therefore be 40 driven at an increased maximum speed, with efficiency. As is well known, when a two or three blade propeller is driven beyond about seventeen to nineteen hundred R. P. M., the efficiency of the propeller is reduced, due to the 45 fact that one blade moves into the space or hole in the air produced by the leading blade. By having only one blade, properly balanced, this disadvantage is overcome, and my one blade propeller may be driven at a speed considerably 50 above the normal efficiency speed of a two or three blade propeller, with efficiency, thus allowing engine to be driven at its maximum efficiency speed. 55

It is to be understood that the form of my invention herein shown and described is to be taken as a preferred example of the same and the various changes in the shape, size, and arrangement of parts, may be resorted to, without departing from the spirit of my invention or the scope of the subjoined claims. 60

Having thus described my invention, what I claim and desire to protect by Letters Patent is:

1. A propeller comprising an elongated rotary element, a bearing device mounted upon the elongated rotary element to rotate therewith and turn upon an axis radially of the rotary element, a second bearing device mounted upon the first named bearing device and capable of swinging in 65 a direction longitudinally of the rotary element and positively turning with the first named bearing device, and a single blade propeller mounted upon the second bearing device, said propeller embodying a blade having unbalanced areas ar- 70

75

- ranged forwardly and rearwardly of the longitudinal axis of the blade and having a centrifugally operated portion adapted to turn the blade upon its longitudinal axis when the pressure upon the blade varies at any given speed of rotation, the first and second named bearing devices serving to rotate the propeller, and means to substantially balance the radial thrust of the propeller.
10. 2. A propeller comprising a rotary element, a bearing device mounted upon the rotary element for rotation therewith and capable of swinging with relation to the rotary element about an axis which is radial with relation to the rotary element, and a single blade propeller pivotally mounted upon the bearing device to turn upon its transverse axis with relation to the bearing device and to turn upon its longitudinal axis with the bearing device, the bearing device serving to 15 rotate the propeller, the propeller embodying a blade having unbalanced areas arranged forwardly and rearwardly of the longitudinal axis of the blade and an enlarged centrifugally operated portion disposed generally at an acute angle 20 with respect to the working face of the blade, the arrangement being such that the pitch of the blade varies as the pressure varies upon the blade when the blade is being rotated at any given speed.
30. 3. A propeller comprising a rotary element, a bearing device mounted upon the rotary element, pivot means between the rotary element and bearing device and disposed radially of the rotary element, a companion bearing device mounted 35 upon the first named bearing device to rotate therewith and capable of turning upon the bearing device in a direction at a right angle to the plane of rotation of the rotary element, the companion bearing device rotating with the first 40 named bearing device, and a single blade propeller comprising a blade having unbalanced areas arranged forwardly and rearwardly of the longitudinal axis of the blade and a centrifugally 45 actuated hub extended laterally in the plane of rotation of the propeller, the hub being arranged at an inclined angle with relation to the working face of the blade, the hub being fixedly secured to the second named bearing device, the first and second named bearing devices serving 50 to rotate the propeller.
4. A propeller comprising a rotary element, substantially radial pivots carried thereby, a bearing unit mounted upon the rotary element and having substantially radial openings to pivotally receive the pivots, said bearing unit embodying webs having cylindrically curved faces extending in a direction at substantially a right angle to the axis of rotation of the rotary element, a single blade propeller element including a blade and a centrifugally operated hub arranged at an inclined angle with respect to the working face of the blade, the working face of the blade having unbalanced areas arranged forwardly and rearwardly of the longitudinal axis of the blade, the hub having an opening formed therein, and bearing blocks fixedly mounted within such opening and having cylindrically curved recesses extending in a direction at a right angle to the plane of 70 rotation of the propeller, said recesses receiving

said webs, the bearing unit and blocks serving to rotate the propeller.

5. A propeller comprising a rotary element, bearing means mounted upon the rotary element and including opposed webs, the webs having outer curved faces extending longitudinally of the longitudinal axis of the rotary element to provide a pivot element having its turning axis disposed at a right angle to the axis of rotation of the rotary element, a propeller element including 10 a blade and hub, said hub having an opening formed therein, bearing blocks arranged within the opening and having recesses to receive the webs, said recesses having outer curved walls extending longitudinally of the longitudinal axis of the rotary element, the bearing blocks turning about the turning axis of the pivot element formed by the webs, elements secured to the opposite sides of the hub to retain the bearing blocks within the opening of the hub, pivot means for 15 mounting the webs upon the rotary element, the pivot means having its longitudinal axis arranged at a right angle to the axis of rotation of the rotary element and at a right angle to the turning axis of the pivot element formed by the webs, 20 means for causing the propeller element to turn upon its longitudinal axis about the pivot means to vary its pitch, and means to substantially balance the radial thrust of the propeller.

6. A propeller comprising a rotary element, oppositely arranged radially projecting webs, said webs having outer curved faces extending longitudinally of the rotary element, the curved faces providing a pivot element having its turning axis at a right angle to the axis of rotation of the 30 rotary element, a propeller element including a blade and hub, said hub having an opening provided with opposed recesses to receive the webs, said recesses having outer curved faces extending longitudinally of the longitudinal axis of the 35 rotary element and engaging the curved faces of the webs, the recesses having side walls to engage with the side walls of the webs so that the webs rotate the propeller, pivot means for mounting the webs upon the rotary element, the pivot 40 means having its turning axis disposed at a right angle to the axis of rotation of the rotary element and at a right angle to the turning axis of the pivot element, means to cause the propeller element to turn upon its longitudinal axis about the turning axis of the pivot means, and means to 45 balance the radial thrust of the propeller.

7. A rotary element, a single blade propeller having unbalanced areas upon opposite sides of its longitudinal axis, means to balance the blade against radial thrust, a centrifugally operated part to turn the blade upon its longitudinal axis, and bearing means to mount the blade upon the rotary element, said bearing means including a pivot element having its longitudinal axis disposed at a right angle to the longitudinal axis of the blade so that the blade may turn thereon and find its plane of rotation and a second pivot element having its longitudinal axis arranged at a right angle to the longitudinal axis of the first 60 pivot element and also extending longitudinally of the longitudinal axis of the blade so that the blade may turn upon its longitudinal axis to vary its pitch.
